(57) **CLAIM**

The ornamental design for a removable pallet kit, as shown and described.

DESCRIPTION

Fig. 1.1 is a top perspective view of the removable pallet kit; Fig. 1.2 is a left side view thereof; Fig. 1.3 is a top plan view thereof; Fig. 1.4 is a front side view thereof; Fig. 1.5 is a right side view thereof; Fig. 1.6 is a bottom plan view thereof; Fig. 1.7 is a rear side view thereof; and Fig. 1.8 is a top perspective view thereof, showing the top removed from the base.

The broken lines illustrate portions of the removable pallet kit that form no part of the claimed design.

This design designates a removable pallet kit that may be used to secure loads during transport by land, sea or air.
